Primary Examiner — Philip S Hyder*Assistant Examiner* — Darlington Ly(74) *Attorney, Agent, or Firm* — Harpman & Harpman(57) **CLAIM**

The ornamental design for a sandblasting gun with trigger, as shown and described.

DESCRIPTION

FIG. 1 is a perspective view of the sandblasting gun with trigger showing my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings illustrate portions of the sandblasting gun with trigger that forms no part of the claimed design.
